DESIGN FOR A TOOTHBRUSH HANDLE

Gilbert E. Hadden, Chicago, Ill.

Application March 8, 1940, Serial No. 90,769

Term of patent 14 years

To all whom it may concern:

Be it known that I, Gilbert E. Hadden, residing at 5607 West Lake Street, in the county of Cook and State of Illinois, have invented a new, original, and ornamental Design for Toothbrush Handles, of which the following is a specification, referring to the accompanying drawing, forming part thereof, in which—

Fig. 1 is a top plan of the toothbrush handle constituting my new design;

Fig. 2 is a side elevation thereof;
Fig. 3 is a bottom plan thereof; and
Fig. 4 is an end view thereof.

I claim:
The ornamental design for a toothbrush handle, as shown.

GILBERT E. HADDEN.
